COMBINATION DEEP-FAT FRYER RANGE, RE-
FRIGERATOR AND FOOD STORAGE UNIT

Donald M. Bull, Eugene, Oreg., assignor to D.A.C.
Investment Corporation, Eugene, Oreg.

Filed Aug. 3, 1971, Ser. No. 168,804

Term of patent 14 years

Int. Cl. D7—02
U.S. Cl. D81—10 C

FIG. 1

FIG. 2

FIG. 1 is a front three-quarter perspective view of a combination deep-fat fryer range, refrigerator and food storage unit embodying my new design; and

FIG. 2 is a back three-quarter perspective view thereof.

I claim:

The ornamental design for a combination deep-fat fryer range, refrigerator and food storage unit, as shown and described.
